DESIGN FOR A GLOVE

Julius A. Higier, Johnstown, N. Y.

Application December 30, 1940, Serial No. 97,712

Term of patent 7 years

To all whom it may concern:

Be it known that I, Julius A. Higier, a citizen of the United States of America, residing in Johnstown, county of Fulton and State of New York, have invented a new, original, and ornamental Design for a Glove, of which the following is a specification, reference being had to the accompanying drawings, forming part thereof, wherein,

The characteristic feature of my design resides in the combination, on the glove disclosed, of the closed end portion shown.

I claim:

The ornamental design for a glove, substantially as shown and described.

JULIUS A. HIGIER.
